UNITED STATES PATENT OFFICE.

WILLIAM H. GRAY, OF EDDYVILLE, IOWA.

APPLE-SORTER.

1,102,496.

Specification of Letters Patent.

Patented July 7, 1914.

Application filed October 28, 1912. Serial No. 728,242.

To all whom it may concern:

Be it known that I, WILLIAM H. GRAY, a citizen of the United States, residing at Eddyville, in the county of Wapello and State of Iowa, have invented a certain new and useful Apple-Sorter, of which the following is a specification.

The object of my invention is to provide an apple sorter of simple, durable and inexpensive construction provided with mechanism whereby apples may be discharged upon a platform having alternate raised portions and having at its lower portions a plurality of traveling conveyers.

15 A further object is to provide such an apple sorter provided with a second traveling conveyer to receive the apples from the plurality of conveyers above mentioned, and provided also with means for rolling the 20 apples forwardly and also laterally on the latter conveyer.

25 A further object is to provide such a device having means whereby the apples are automatically separated into assorted sizes, and whereby each size is delivered into a receptacle provided therefor.

30 My invention consists in certain details, in the construction, arrangement and combination of the various parts of the device, whereby the objects contemplated are attained, as hereinafter more fully set forth, pointed out in my claims, and illustrated in the accompanying drawings, in which:

35 Figure 1 shows a top or plan view of an apple sorter embodying my invention. Fig. 2 shows a vertical, sectional view through the same. Fig. 3 shows a transverse, vertical, sectional view taken on the line 3—3 of Fig. 2. Fig. 4 shows a transverse, sectional view taken on the line 4—4 of Fig. 2. Fig. 5 shows a transverse, sectional view taken on the line 5—5 of Fig. 2, and Fig. 6 shows a detail view of a part of the mechanism.

40 In the accompanying drawings, I have used the reference numeral 10 to indicate generally the supporting frame of my improved apple sorter.

45 At what I will call the rear end of my apple sorter, I have provided a plurality of longitudinally arranged traveling conveyers 11 between which are raised portions 12 of the frame which, in all cases, slope downwardly toward the adjacent conveyer 11, and which are covered with some soft material 13 such as sheepskin or the like. The

portions 12 between the conveyers may have the form of an inverted V in cross section with each side inclining toward one of the conveyers 11. The upper parts of the conveyers 11 travel in the direction indicated by the arrow in Fig. 1; that is, from the rear toward the front of the machine.

50 In beginning the sorting of my apples, I pour the apples upon the parts 12 and the conveyers 11 and the apples only roll down to the conveyers. The conveyers 11 may be provided with short transverse slats 14. I preferably provide under the upper portions of the conveyers 11 a smooth platform 15 to 55 support the conveyers 11 in substantially horizontal position; the conveyers 11 travel over rollers 16 and 17 arranged at the rearward and forward ends respectively of said conveyers. The rollers 16 are fixed upon a 60 shaft 18 and the rollers 17 are loosely mounted upon a pipe or tube 19. At the sides of the platform 15 are vertical walls 20 and at the rear end of the walls 20 I provide an inclined end member 21. The rear ends of the 65 walls 20 may be supported by ropes or the like 22 which permit the lateral movement of the platform 15 hereinafter more particularly referred to. Arranged in front of the conveyers 11 and slightly below the level 70 thereof, in position to receive the fruit discharged from the conveyers 11, is a broad traveling conveyer 22 of proper width to receive the fruit discharged from all the 75 conveyers 11. The conveyer 22 travels upon rollers 23 and 24 at its rear and front ends respectively. The rollers 23 and 24 are mounted upon shafts 25 and 26, the shaft 26 being a power shaft and the shaft 25 being 80 an idler shaft, as hereinafter more fully set forth.

85 Mounted upon the frame of my improved apple sorter, below the forward end of the conveyer 22, is a transverse shaft 27 capable of sliding movement with relation to said frame. At each end of the shaft 27 is an upwardly extending arm 28. Connecting the upper ends of the arm 28 is a transverse bar 29. Extending downwardly from the bar 29 to position spaced above the upper portion of the conveyer 22, is a plurality of brackets 30. Rotatably mounted in the brackets 30 is a plurality of horizontal longitudinally arranged rods 31 extending from said brackets rearwardly to the tube 19 90 in which the rear ends of said rods are mounted. The rods 31 are preferably cov-

ered with rubber tubing 32 or other suitable means for preventing the bruising of the fruit.

Connecting the lower edges of the side members 20, at the forward ends thereof, are two transverse members 33. Mounted on the frame of the device below the forward ends of the conveyers 11 is a transverse shaft 34. Slidably mounted upon the shaft 34 are upwardly extended arms 35 secured at their upper ends to the transverse members 33. Suitably mounted upon the frame on each side thereof adjacent to the rear ends of the rods 31 are upwardly extending arms 36. Extending rearwardly from the members 36 are brackets 37, the rear ends of which are approximately on a level with the rear ends of the rods 31. Connecting the brackets 37 is a flexible device 38 such as a rope which is preferably wound once around each of the rods 31, as clearly shown in Fig. 5.

It has already been noted that the rear end of my apple sorter is supported by the ropes 22^a. The forward end of the rearward section which carries the conveyers 11 is slidably mounted upon the shaft 34 and is capable of lateral sliding movement with relation to the fixed portions of the frame 10. The rear ends of the rods 31 are fixed in the tube 19 which moves with the rearward portion or section of my apple sorter. The forward ends of said rods 31 move with the brackets 30 and the brackets 30 may be moved laterally by sliding the shaft 27 laterally. The mechanism whereby the shaft 27 and the arms 35 are moved laterally will be now more fully explained:

The shaft 26 extends outwardly at one end and mounted thereon is a belt pulley 40 which may be operatively connected with any suitable source of power. Upon the outer end of the shaft 26 outside the belt pulley 40 is a wheel 41 having a cam face 42. Mounted upon the frame 10 below the shafts 26 and 34 are laterally extending brackets 43. Rotatably mounted in the outer ends of the brackets 43 is a longitudinally arranged rock shaft 47. Fixed to the rock shaft 47 beneath the shaft 26 is an upwardly and outwardly extending arm 44. On the outer end of the arm 44 is a roller 45 designed to engage and travel on the cam face 42 of the wheel 41. The arm 44 is held at the inward position of its movement by means of a contractile coil spring 46 secured to said arm and to the fixed portion of the frame of the machine. Fixed on the rock shaft 47 is an upwardly extending arm 48. Pivoted to the upper end of the arm 48 is a link 49 standing in substantially horizontal transverse position, and pivoted to one of the arms 28.

The parts just described are so arranged that when the shaft 26 rotates the wheel 41

the roller 45 traveling upon the cam face 42 will actuate the arm 44 and thereby the rock shaft 47 which, through the arm 48 and the link 49, will reciprocate the arms 28 laterally, thereby moving the member 29 and the brackets 30 and the rods 31. Extending upwardly from the rear end of the rock shaft 47 is an arm 50. A substantially horizontal link 50^a is pivoted at one end to the arm 50 and at the other end to one of the arms 35. When the rock shaft 47 is rotated the forward ends of the conveyers 11 will be swung or reciprocate laterally through the tube 19, the ends of which are mounted in the sides 20, the transverse member 33, the arms 35, the link 50^a, and the arm 50. It will be seen that, by the arrangement of the rope 38, when the rods 31 are moved laterally, they will also be rotated at the same time. The purpose of reciprocating the rearward section of the machine which carries the conveyers 11, and of reciprocating the rods 31 laterally thereof, is to cause the apples on the conveyer 22 to roll, making it possible for anyone standing at the side of the machine to detect any bad spots in the apples and to pick out and remove any defective fruit. The rotation of the rods 31 by means of the rope 38 assists in rolling the apples. The apples are therefore rolled in one direction by the action of the traveling conveyer 22 and in another direction by the lateral reciprocation and the rotation of the rods 31.

The traveling conveyers 11 and 22 are operated in the following manner: The rollers 24 are mounted upon the shaft 26 which is rotated by means of power applied to the pulley 40. The roller 26 carries the conveyer 22 which operates the roller 23 and the shaft 25. Upon one end of the shaft 25 is a belt pulley 50^b. Upon one end of the shaft 17 is a belt pulley 51 in line with the pulley 50^b. A belt 52 travels upon the pulleys 50^b and 51.

In the drawings, I have shown four of the conveyers 11, the space between the two central conveyers being somewhat wider than the space between the outer conveyers. The rods 31 are arranged in pairs so that the apples from each of the conveyers 11 will be discharged between a pair of the rods 31. I have left a space in the center of the conveyer 22 which is indicated by the reference character A free from the rods 31. As the apples are rotated in passing over the conveyer 22, the defective apples are picked up and dropped into the space A. The apples from the space A are discharged into a chute 58. I have arranged adjacent to the discharge end of the conveyer 22 guide chutes or devices 53 arranged to discharge the fruit from the conveyer 22, except the portion A thereof, in two streams. For receiving the apples discharged from

the conveyer 22 and for sorting them into sizes and delivering them into receptacles according to their sizes, I have provided the following means: Mounted in the frame 5 10, adjacent to the two points of discharge from the conveyer 22, I have provided spirally corrugated shafts 55 covered with suitable soft material. The shafts 55 may incline from the rearward ends forwardly 10 and downwardly. Spaced apart from the shafts 55 are parallel shafts 56. The shafts 56 are constructed with portions 57, each of which is covered with soft material. The portions 57 are graded in sizes and are arranged in a series, the portion 57 having 15 the greatest diameter being at the rearward ends of the shafts 56, then the next smaller portion 57, and so on. It will thus be seen that the space between the portions 57 and 20 the adjacent shaft 55 is increased toward the outer ends of the shafts 55. The space between the rearward portion 57 and the shaft 55 is quite small and permits the smaller apples to pass between said shaft and said portion. The space between the 25 next portion 57 and the shaft 55 permits slightly larger apples to drop down between said portion and said shaft and so on. Beneath the various portions 57 is a plurality 30 of guide chutes 59 lined with soft material and designed to discharge into suitable receptacles 60.

The shafts 55 and 56 are rotated so that their movement to the apples will always 35 be upward in the following manner: Mounted below the shaft 26 is a transverse shaft 61. Upon one end of the shaft 26 is a pinion 62 in mesh with the pinion 63 on the shaft 61. Upon the upward rearward 40 ends of the shafts 55 and 56 are beveled gears 64 in mesh with beveled gears 65 on the shaft 61. The beveled gears 64 and 65 are so arranged that the movement of the shafts 55 and 56 is always upward with 45 relation to the apples between them.

For brevity's sake, I shall refer to that portion of my apple sorter which carries the conveyers 11 as the first section; to that portion which carries the conveyer 22 as 50 the second section, and to that portion which includes the portions 57 as the third section.

In the practical use of my improved apple sorter, the apples are discharged upon the top of the first section in any suitable manner. The construction of the portions 13 causes the apples to move downwardly to the conveyers 11 by which they are moved forwardly in the machine and are discharged upon the conveyer 22. The machine is operated from any suitable source of power applied to the belt pulley 40. When the apples are discharged upon the conveyer 22 they are carried forward by said conveyer and are also rolled laterally 55 by the lateral reciprocation of the rods 31.

Persons standing on each side of the machine may watch the apples upon the conveyer 22 and pick out the spoiled or defective fruit placing it in the space or portion A. From the conveyer 22, the defective 70 fruit is discharged into the trough or spout 58 and the good fruit passes into the spaces between the shafts 55 and the portions 57. The smaller apples are dropped into the first receptacle 60, the next larger apples into 75 the second receptacle 60, and so on. When the operation is completed the defective apples will have been separated from the sound ones and the sound apples will have been graded according to size. 80

It will be understood that a great many variations may be made in the details of the construction of my improved apple sorter, it being my intention to cover any variation in the construction coming within the scope 85 of the appended claims.

In my illustrated description, I have referred frequently to apples but it is to be understood that I do not confine myself to the use of my machine with any particular 90 kind of fruit.

I claim as my invention:

1. In a device of the class described, a traveling conveyer, parallel rods arranged longitudinally above said conveyer in pairs, 95 the members of each pair of rods being spaced apart from each other to receive fruit between them, means for reciprocating said rods laterally to alternately rotate the fruit upon said conveyer as it is advanced, 100 and means for arranging fruit in parallel rows and feeding it continuously between the members of each pair of rods.

2. In a device of the class described, a traveling conveyer, a frame above said conveyer capable of transverse movement, parallel rods arranged in pairs in said frame longitudinally above said conveyer, the members of each pair of rods being spaced apart from each other to receive fruit between them, and means for reciprocating said frame transversely to alternately rotate the fruit upon said conveyer as it is advanced. 105

3. In a device of the class described, a traveling conveyer, a series of longitudinally arranged rods mounted above said conveyer in parallel pairs, means for reciprocating said rods laterally, and means for rotating said rods when they are so reciprocated. 115

4. In a device of the class described, a traveling conveyer, parallel rods arranged longitudinally above said conveyer in pairs, the members of each pair of rods being spaced apart from each other to receive fruit 120 between them, means for reciprocating said rods laterally to alternately rotate the fruit upon said conveyer as it is advanced, and means for rotating said rods when they are so reciprocated. 125

5. In a device of the class described, a traveling conveyer, parallel rods arranged longitudinally above said conveyer in pairs, the members of each pair of rods being spaced apart from each other, means designed to arrange fruit in parallel rows and designed to feed it continuously between the members of each pair of rods, means for reciprocating said rods laterally to alter-

nately rotate the fruit upon said conveyer as it is advanced, and means for rotating said rods when they are so reciprocated.

Des Moines, Iowa, October 15, 1912.

WILLIAM H. GRAY.
